JEWEL BANGS WILLIAMS, OF CINCINNATI, OHIO, ASSIGNOR TO THE TRIUMPH ELECTRIC COMPANY, OF CINCINNATI, OHIO, A CORPORATION OF OHIO.

WATER-AGITATOR FOR ICE PLANTS.

1,194,108.

Specification of Letters Patent. Patented Aug. 8, 1916.

Application filed December 13, 1915. Serial No. 66,58

To all whom it may concern:

Be it known that I, JEWEL BANGS WILLIAMS, a citizen of the United States, residing at Cincinnati, in the county of Hamilton and State of Ohio, have invented new and useful Improvements in Water-Agitators for Ice Plants, of which the following is a specification.

My invention relates to apparatus for manufacturing ice and particularly to water agitators for use in ice factories.

In ice plants, ice cans immersed in the cold brine are usually arranged in rows both lengthwise and crosswise, with a space between. In this space, in raw water plants, midway between the rows of cans, is a main for distributing air, with an outlet opposite the center of each pair of cans. A yoke made of pipe is used to convey air from each of the main outlets to the interior of the can on either side. While the water in the cans is being frozen, the yoke is in place astride the air main at the outlet, and air at low pressure is thus introduced into the water in each pair of cans. This keeps the water agitated while it is being frozen, which is important particularly in raw water plants, as the freezing water is freed of impurities. The water near the can surfaces freezes first, and the impurities are therefore gradually forced toward and collected near the middle of the can, and removed when ice-making has proceeded to the proper point. From this it will be seen that it is important to have the drop pipes of the yoke placed and kept as near the center of the cans as possible, as there the water naturally freezes last. When the small remaining quantity of water with its accumulated impurities in the center of the ice cake in the can is to be drawn off, the yoke is removed. Sometimes, the outlets on the air main are not closed, but the air allowed to waste freely. Sometimes, they are provided with check valves which close when the yoke is removed and sometimes they are covered or plugged.

My improvements provide unitary valve controlling means to hold a check valve in the outlet open when the yoke is in place, and means for requiring such placing of the yoke as will put the drop pipes of the yoke in the center of each can in order to open the valve.

The device used to accomplish both pur-

poses is so designed as to be very cheaply made and can be readily handled by the common labor used in such plants. There are no loose plugs or caps to lose, and nothing that would get out of order with ordinary use.

Ice cans may be arranged in any convenient manner, so that a definite arrangement is adhered to, and the yoke or manifold and its connections made to fit that arrangement.

In the particular embodiment of my invention selected for illustration: Figure 1 is a top plan view of a number of ice freezing cans with parts of air mains and agitating yokes in position for use. Fig. 2 is an elevation of one of the yokes in position, and indicated as in operation, with the air main and ice cans in section. Fig. 3, a detail, is a vertical longitudinal axial section 70 through the yoke T, and a vertical axial cross section of the air main outlet and valve. Fig. 4, a detail, is a vertical axial cross section of the yoke T, and a vertical axial longitudinal section of the air main, 75 its outlet and valve. Fig. 5, a detail, is an under plan view of the yoke at its T.

In the drawings, A represents the air main, midway between rows of ice cans, with outlets, a, opposite each pair of cans, C, C'. The outlet member, a, forms a casting for a valve, a¹, open at its upper end, a², enlarged at its closed lower end, a³, where it seats against the end of the outlet member, provided with any convenient openings, a⁴, to facilitate the passage of air to the manifold or yoke, B, (hereinafter described), when the valve is open, and having a lug, a⁵, to suitably limit its downward movement. The valve is held open by gravity, but air pressure (normally about 3 pounds to the square inch) in the air main, pressing upwardly against the under end, a³, of the valve, raises it and causes it to seat when its upward movement is not interfered with. The outlet member has a vertical slot, a⁶, cut in either side to admit a pin as will hereinafter be described. This slot is lengthwise of the air main, A.

B represents a yoke composed of drop pipes, b, b¹; L's, b², b³; extension pipes, b⁴, b⁵; and manifold or T, b⁶. The extension pipes b⁴, b⁵, are of such length as when the extension pipes are at right angles to the air main, A, to bring the drop pipe, b, in the 105 110

center of can C, and the drop pipe, b¹, in the center of can C¹. A pin, b⁷, fixed in the opening of the manifold, b⁸, transversely, is adapted to seat in the slot, a⁶, of the outlet, 5 a, so as to fit the yoke and hold it at right angles to the air main, A.

When the yoke is in position for use, the pin, b⁷, prevents the valve, a¹, from seating, hence air flows freely from the main through 10 the yoke to each of the cans opposite the outlet member of that particular yoke. Immediately upon the removal of the yoke, the valve closes, as its upward movement is no longer checked. The yoke will not seat so 15 as to be operative unless in position for the pin, b⁷, to enter the slot, a⁶, and when in that position, the drop pipes on the yoke are in the center of their respective cans.

I do not wish to limit myself to the precise 20 form of mechanism herein described and shown, but understand my invention covers any modifications thereof that will provide an air main with a valve and a yoke to deliver air therefrom to the center of adjacent 25 cans, the valve automatically closing when the yoke is not in position for delivery of air to the cans.

Obviously, instead of two cans only being 30 in line with and supplied with air from one valve on the main, a greater number of ice cans could be placed in line; and the yoke extended on one or both sides, or in any other convenient way, as the cans were arranged, to supply air to all the cans in that 35 row or group, or as many as were desired.

Any arrangement of cans and mechanism for supplying compressed air thereto, may be used; the gist of my invention being the unified means of controlling the air valve 40 and centering the drop pipes in the ice cans.

I claim as my invention, and desire to secure by Letters Patent of the United States:—

1. In water agitators for ice plants, where 45 ice cans are used in any fixed position for ice making, the combination of a pipe for supplying air under pressure, an outlet member in said air supply pipe, a valve adapted to close said outlet by air pressure 50 from within said pipe, a manifold and connections for conveying air from said outlet to the centers of a plurality of ice cans, and unitary means for simultaneously opening said valve, and for centering said manifold; 55 said unitary means being adapted to keep said valve open so long as the manifold remains in said position and to hold the said manifold and its connections in said positions against accidental displacement.

2. In water agitators for ice plants, where 60 ice cans are used in any fixed position for ice making, the combination of a pipe for supplying air under pressure, an outlet member in said air supply pipe, a valve adapted to close said outlet by air pressure 65 from within said pipe, a guide on said outlet member for centering a manifold, a manifold and connections for conveying air from said outlet to the centers of a plurality of ice cans, and means for uniting the manifold 70 with the guide on the outlet member to center the manifold, and the manifold so formed as to open the valve and hold it open only when and so long as the manifold is centered on said outlet member. 75

3. In water agitators for ice plants, the combination of a pipe for supplying air under pressure between rows of cans in pairs, an air outlet opposite the center of the cans of each pair, a valve adapted to close said 80 outlet by air pressure from within, a manifold and connections for conveying the compressed air from the supply pipe to said cans and means for simultaneously holding said valve open and the manifold drop pipes in 85 the center of said cans.

4. A water agitating device for artificial ice plants, having in combination an air main, an air outlet from said main, a valve within said outlet adapted to close by being 90 raised by air pressure within the main, vertical slots in the top of said air outlet, a yoke of such size and shape as to form conduits from the air outlet to an ice can on either side of the main opposite the air outlet, and 95 means on the yoke for operatively connecting the air outlet through the yoke with the cans only when the yoke is so placed astride the main as to place the drop pipes of the yoke in the center of the contiguous ice cans. 100

5. In water agitating apparatus of the character indicated, a main distributing air-conduit having a service outlet; a self-seating valve controlling said outlet; a removable service manifold adapted to be connected with said outlet; and unitary means for securing said connection and maintaining the proper service relation of the manifold to the distributing main, and at the same time maintain the outlet-controlling 110 valve in open position.

In testimony whereof I have hereunto set my hand in presence of two subscribing witnesses.
